UNITED STATES PATENT OFFICE.

FRANK H. HOYT, OF SHARON, PENNSYLVANIA.

WASTE-PIPE CLEANER.

SPECIFICATION forming part of Letters Patent No. 532,376, dated January 8, 1895.

Application filed August 11, 1894. Serial No. 520,091. (No model.)

To all whom it may concern:

Be it known that I, FRANK H. HOYT, a citizen of the United States of America, residing at Sharon, in the county of Mercer and State of Pennsylvania, have invented certain new and useful Improvements in Waste-Pipe Cleaners, of which the following is a specification.

The object of my invention is to provide means for cleaning and removing obstructions in waste pipes leading from sinks.

My device as will be described hereinafter comprises a plate adapted to be removably attached to the strainer secured in the sink, and is provided with a nozzle screwed therein.

15 A hose is attached to the upper end of this nozzle and to a water cock, and the water is thereby forced in a small stream through the waste pipe. The nozzle is directly over the central perforation in the strainer, and all the other 20 perforations in said strainer are closed by a gasket interposed between the plate and strainer.

The invention is illustrated in the accompanying drawings, in which—

25 Figure 1, is a side elevation of the device applied to the strainer and sink, part of the sink being shown. Fig. 2, is a central vertical section.

A section of a sink of ordinary construction 30 is shown at 1 to which is secured the strainer 2 covering the mouth of the waste pipe 3. To this strainer the cleaner is attached. It consists of the plate 4 having its under face made to conform to the shape of the strainer, and 35 in the center of this plate is screwed the nozzle 5. The plate is attached to the strainer by means of the clips 6 having one of their ends screw threaded. One arm of each of these clips bears on the under side of the strainer. 40 The other or threaded arm extends through perforations in the plate and through openings in the bosses 6^x formed on the plate 2. A thumb nut 7 screws on the threaded end of said arm 6 and the under side of said nut bears 45 on the top of the bosses 6 to clamp the plate 2 and strainer together. Interposed between

the plate 2 and the strainer is a gasket 8 preferably of rubber. This gasket effectually covers all the openings in the strainer except those directly beneath the discharge opening 50 in the nozzle 5 and thus all the water is forced through these central perforations.

To clean a sink this device is attached to the strainer and a hose secured to the nozzle and to a water cock. The water is forced 55 through the nozzle and the perforations beneath said nozzle. The stream of water is so contracted by passing through these small openings that a great pressure is given thereto, sufficient to effectually cleanse the drain 60 pipe or discharge any obstructions therein.

I claim—

1. In a device for cleansing waste pipes, in combination with the strainer covering the mouth of said pipe, the plate formed to fit 65 the contour of the face thereof, the nozzle screwed in the center of said plate, the bosses on each side of said nozzle, having openings therein, the clips passing through said openings and having laterally bent ends adapted 70 to bear on the under side of the strainer and the nuts adapted to be screwed on the upper end of said clips for clamping the said strainer and plate together, substantially as described.

2. In a device for cleansing waste pipes, in 75 combination with the strainer covering the mouth of said waste pipe, the plate, the nozzle carried thereby, the clips and the thumb nut, connecting said plate and strainer, and an interposed rubber gasket between the plate 80 and strainer surrounding the opening in said nozzle to close the perforations in said strainer surrounding said opening, said nozzle adapted to have a hose connected thereto and to the water cock, substantially as described. 85

In testimony whereof I affix my signature in presence of two witnesses.

FRANK H. HOYT.

Witnesses:

LEVI HIGGINS,
A. W. WILLIAMS.
